UNITED STATES PATENT OFFICE.

JOHN G. BLESSING, OF CHICAGO, ILLINOIS, ASSIGNOR TO JOSEPH E. COCHRAN, OF CHICAGO, ILLINOIS.

WEIGHING-SCALE.

No. 821,214.

Specification of Letters Patent.

Patented May 22, 1906.

Application filed March 18, 1905. Serial No. 250,817.

To all whom it may concern:

Be it known that I, JOHN G. BLESSING, a citizen of the United States, residing at Chicago, in the county of Cook and State of Illinois, have invented a certain new and useful Improvement in Weighing-Scales, of which the following is a specification.

My invention relates to weighing-scales, and is related in general to the companion application filed by me this day, Serial No. 250,816.

The object of the present invention is to provide a dial rotatable about a horizontal axis and having a number-surface greater than the surface which would be afforded by a flat dial having the same exterior diameter.

I am not the inventor of and do not claim the method of constructing the scale-beam rack nor the pivoting thereof to the scale-beam.

I attain my object by the mechanism illustrated in the accompanying drawings, in which—

Figure 1 is a side elevation of a complete machine. Fig. 2 is a plan view thereof. Fig. 3 is a vertical sectional view taken on line 3-3 in Fig. 2. Fig. 4 is a face view of the cap and dial looking in the direction of the arrow in Fig. 3. Fig. 5 is a fragmentary view showing the construction of the guide or keeper for preventing the scale-beam rack from becoming unmeshed from the dial-shaft pinion. Fig. 6 is a side view of the computing-dial indicating the preferred general arrangement of the numbers thereon.

Similar letters refer to similar parts throughout the several views.

The scale-beam *a* is fulcrumed upon the post *b* of the main frame *b* and carries at one extremity the scale-pan *c* and at the opposite extremity means for transmitting motion to the dial-shaft. In the preferred construction here shown the transmitting means consists of a rack *d*, which is pivoted to the extremity of the scale-beam and conforms to the arc of a circle having as a radius the distance between the scale-beam fulcrum and the point of attachment of said rack to the scale-beam. Said rack is adapted to mesh with the pinion *e*, rigidly secured to shaft *f*, which lies horizontal and has a stationary bearing at each extremity. In order that the rack *d* may at all times tend to approach

said pinion *e* to make close contact therewith and avoid backlash, it is desirable to provide said rack with a weighted arm *d'*, extending approximately at right angles thereto, as best shown in Fig. 1. A stationary guard or keeper *d*² should be provided for preventing said rack *d* from becoming unmeshed from pinion *e*.

The dial *g* is conical and concentric with shaft *f* and is rigidly mounted thereon, so as to rotate therewith. Arranged in concentric circles upon said dial are series of product-numbers *g'* after the well-known manner of computing-scales and as more fully described in my companion application above referred to. It is desirable also to provide a series *g*² of numbers running from zero up for indicating the weight in pounds. These are best placed at the outer peripheral edge of the dial concentric with the product-numbers and having the zero upon the same elemental line with the zeros of the product-numbers.

The reading member *h* has marked thereon a series of numbers representing multipliers *h* or, in the case of the ordinary computing-scale, the "price-per-pound" numbers. These numbers are so arranged that each one will come adjacent to its respective row of product-numbers on the dial. A reading-line *h*² should be marked or formed upon said reading member for affording a "line of sight" against which the product-numbers may be read. In the preferred form said reading member consists of a strip of glass supported at a point adjacent to and in front of the dial, as mentioned in my companion application.

In order to protect the dial, it is desirable to provide a cap *i*, which is conical in form and conforms closely to the configuration of the dial. Said cap may be, if desired, integral with the frame *b*, as illustrated in Fig. 3. When such an opaque cap is employed and the reading member *h* consists of glass, said cap has a slot *i'* therein for exhibiting the weight-numbers.

In computing-scales used, for example, by retail merchants it is desirable that both the merchant and the customer shall be able to simultaneously obtain a reading, and therefore I have provided a second dial *j*, located at the base of dial *g* and arranged at right angles to shaft *f*. Said dial *j* is rigidly secured to shaft *f* or dial *g*, or both, so as to

rotate therewith, and has, preferably, at or near its peripheral edge a series of numbers j' , running from zero up and intended to indicate pounds weight.

- 5 For protection it is desirable to inclose the dial j as well as dial g , and for this purpose a plate k , preferably similar in outline and of a diameter slightly greater than the diameter of dial j , is secured in front of the latter by 10 being fastened to framework b or other stationary part of the device. In order to exhibit the weight-numbers j' at the reading-point, a slot or opening k' is formed in said plate k , which opening may be glass covered, 15 if desired.

I have described dial g as being conical with its axis of revolution coincident with shaft f . It is obvious, however, that said dial need not constitute a complete cone with 20 a pointed apex. On the contrary, any right frustum of a cone will operate in the same manner for the same purpose.

In my companion application I have referred to the advantage in employing a conical dial which affords a greater surface for receiving numbers than is afforded by a flat dial of the same diameter. This advantage of course is also inherent in my present device, and a second advantage is also present—to wit, the plane of the reading member and adjacent parts of the dial approximately perpendicular to the line of vision of an observer looking from a point above and at the side of the scale. This not only avoids error 35 in reading due to parallax, but increases convenience in reading. There is an additional important advantage in mounting the conical dial upon a horizontal shaft, for it becomes unnecessary to employ bevel or miter 40 gears for transmitting motion from the scale-beam to the dial-shaft.

With the construction here shown the rack d , which is pivoted directly to the scale-beam, meshes directly with the spur-pinion 45 e , which is concentric with and rigidly secured directly to the dial-shaft f . There is thus produced a scale having two dials which may be read from opposite sides of the scale, one of them having a reading portion oblique 50 to the horizontal, and yet the whole employs but a single gear connection, the consequence being that backlash is reduced to a minimum.

What I claim as new, and desire to secure by Letters Patent, is—

1. In a weighing-scale, the combination 55 with the scale-beam and beam-support, of a horizontal dial-shaft, a conical dial concentric with said shaft, a flat circular dial disposed transversely to and concentric with said shaft, a casing for concealing all but a certain 60 portion of said dials for facilitating the reading thereof, and connections between the scale-beam and said dials for rotating the latter; said flat dial being coincident with the base of the conical dial, the two dials thereby 65 constituting a single cone.

2. In a weighing-scale, the combination 70 with the scale-beam and beam-support, of a horizontal dial-shaft, a conical dial concentric with said shaft, a flat circular dial concentric with 75 said shaft and lying transverse thereto, said dials rotating as a single piece and the flat dial forming the base of a cone in which the conical dial forms the sides, and connecting means including gears for rotating said dials 80 from the motion of the scale-beam, said connections lying outside of the cone formed by said two dials.

3. In a weighing-scale, the combination 85 with the scale-beam and beam-support of a horizontal shaft, a conical dial concentric with said shaft, a flat circular dial disposed transversely to and concentric with said shaft, connections between the scale-beam and said dials for rotating the latter, said flat 90 dial and conical dial being contiguous and together forming a cone, and a cone-shaped casing closely fitting over said dials, the connections from the dials to the scale-beam being located between the said flat dial and the 95 adjacent portion of the casing, and said casing having apertures therein through which the dials may be read, and transparent glass plates covering said apertures and having a reading-line marked thereon, substantially as described.

In witness whereof I have hereunto subscribed my name in the presence of two witnesses.

JOHN G. BLESSING.
